CLAMP FOR PIPE WELDING OR THE LIKE

Oren B. Harmes, Algona, Iowa, assignor of one-half to Ladish Co., Tri-Clover Division, Kenosha, Wis., a corporation of Wisconsin

Filed Feb. 1, 1960, Ser. No. 59,209

Term of patent 14 years

(Cl. D54—13)

FIG. 1 is an elevational view of one side of a clamp for pipe welding or the like embodying my new design.
FIG. 2 is an elevational view of the other side thereof;
FIG. 3 is a top plan view; and
FIG. 4 is a view taken from the lower left hand corner of FIG. 1.

I claim:

The ornamental design for a clamp for pipe welding or the like, as shown.
